RELIEF VALVE

Robert Stevenson and Alexander W. Keema,
Providence, R. I., assignors to Merit Engineering, Inc., a corporation of Rhode Island

Application September 18, 1942, Serial No. 458,902

1 Claim. (Cl. 137—53)

This invention relates to a relief valve such as may be used to control the storing of fluid at a certain predetermined pressure in a reservoir or the like for operating some work unit.

One of the objects of this invention is to provide a valve which will be so arranged that a light spring may be utilized for controlling the valve.

Another object of this invention is to provide a simply controlled valve and yet one which will operate satisfactorily under high pressures.

Another object of the invention is to provide a valve which will be partially balanced by the pressure which it controls with a spring to cause movement of the plunger in one direction to close the valve against a differential pressure which may be overcome upon building up of the pressure.

With these and other objects in view, the invention consists of certain novel features of construction, as will be more fully described and particularly pointed out in the appended claim.

Fig. 1 is a top plan view of the valve;

Fig. 2 is a central section view;

Fig. 3 is a fragmental detail on an enlarged scale from that shown in Fig. 2 and illustrating diagrammatically the difference in diameters of the effective areas upon which the fluid pressure exerts force;

Fig. 4 is an elevation showing an arrangement for supplying and of storing of fluid at pressures of different values from a single pump.

In proceeding with this invention we have provided a plunger having a longitudinal conduit so that the pressure to which the valve is exposed presses against both ends of the movable plunger whereby the differential of the effective diameters against which the fluid presses will govern the movement of the plunger, it being desirable that the diameter against which the pressure acts to move the plunger to closed position shall be less than the area tending to open the plunger and that this lesser diameter will be supplemented by a light spring pressing in an amount to just overcome the larger area or diameter until the fluid pressure builds up to a predetermined extent when the plunger will move to compress the spring.

With reference to the drawing, 10 designates the body of generally cylindrical construction having a cylindrical bore 11 restricted as at 12 to provide a beveled valve seat 13 from which restriction there is an entrance opening 14 to the chamber 11 which connects with the conduit 15 along which fluid is passed from the supply pump to the reservoir for storing the fluid and along which fluid will pass until it exceeds a predeter-

mined pressure. An exit 16 from chamber 11 is provided while at the upper end of the cylindrical chamber 11 a lining sleeve 17 is inserted and is held in place by a closure cap 18 bolted to the body as at 19 with heads 20 having slots 21 engaging the flange 22 of the body 10.

A piston 23 slidably fits lining 17 and is provided with grooves 18 and packing 19 to prevent passage of the fluid along the surface of the piston between it and the lining 17. The piston is reduced in diameter as at 24 while at its lower end it is bevel shape as at 25 to fit the valve seat 13. The longitudinal bore 26 is provided extending throughout the axial length of the piston and at its upper end the piston is provided with an enlarged bore 27 to receive spring 28 which abuts at the lower end of this bore as at 29 and also abuts the collar 30 on the threaded plug 31 which threadingly engages the cap 18 and is packed against leakage as at 32 while it is held in adjusted position by the check nut 33. The lower end of this plug is reduced to provide a guide 34 for the spring.

The fluid which is provided in conduit 15 passes through the bore 26 and will press upon the top of the plunger 35 and will also press upon the lower end of the plunger 36. The relative diameters of the ends of the plunger are illustrated by A and B (see Fig. 3), it being noted that the diameter B is greater than the diameter A. Thus the greater force is exerted tending to move the plunger from its seat but by reason of the spring 28 this force is overcome at certain predetermined pressure conditions and thus the plunger will engage the seat 13 and be maintained thereagainst by a light spring pressure. However, when the pressure rises beyond the predetermined point at which the spring 28 is set by means of the adjustment 31 the differential will increase and be such as to exceed the pressure of the area A plus the spring and move the plunger from its seat. The areas A and B may be varied to supply the different conditions necessary for operation.

This relief valve which we have provided is shown hooked up in multiple in Fig. 4 and as a whole is designated 40, 40', 40''. The conduit 41 extends from the pump through the conduit 15 of the valve to supply fluid to an accumulator 42 which for the sake of illustration may be assumed desired to accumulate the fluid at 1,000 lbs. Accordingly, the spring 28 in the relief valve will be set so that when the pressure of 1,000 lbs. is provided in the accumulator 42 the valve will open. The fluid will then pass through conduit 43 to the next valve 40' and will pass through

the conduit 15 to supply the accumulator 44 with fluid, for example at 500 lbs. pressure. The spring 28 of this valve 40' will be set to permit the plunger to open when a pressure of 500 lbs. of fluid is provided in the accumulator 44 so as to communicate with the conduit 45 which conducts the fluid to the valve 40'' where the fluid will pass through the conduit 15 to the accumulator 46 which will be desired to accumulate fluid for example at 100 lbs. Thus, the spring 28 of the valve 40'' will be set to open at 100 lbs. so that the conduit 47 will convey fluid back to the pump or to some other relief source when the pressure in the accumulator 46 has reached 100 lbs. By this arrangement from a single pump we may supply accumulators at varying pressures depending upon the setting of the relief valve which we provide.

We claim:

In a relief valve, a one-piece body provided with a cylindrical bore reduced at one end to form an inlet having a shoulder forming a valve seat, a plunger slidable in said bore and having a head portion at one end engaging said seat and provided at the other end thereof with a piston having a recess opening in the end thereof, said plunger being provided with an axial conduit from said valve seat engaging portion to said recess subjecting its opposite end to the pressure in the inlet, whereby the said pressure to be relieved will press upon the ends of said plunger

in accordance with the differential of the diameters of the said ends of the plunger exposed to said pressure, the diameter of the piston being less than the effective diameter of the head, a sleeve mounted in the cylindrical bore for slidably receiving said piston, a cap engaging said sleeve and closing said cylindrical bore, a spring in said recess additionally urging the plunger toward the valve seat and exerting sufficient force to maintain the plunger in closed condition until the pressure in the inlet increases to a predetermined extent to cause the pressure differential to overcome the added spring pressure and the fluid pressure on the plunger to move the plunger from its seat, an abutment engaging one end of said spring, a threaded member extending through the cap operable for adjusting the pressure of said spring and having one end engaging said abutment and having its other end extending outwardly of said valve body, a packing recess in said cap about said threaded member, a packing surrounding said threaded member and located in said packing recess, and a check nut engaging said threaded member and having a boss entering said packing recess to engage said packing for compressing said packing about said threaded member and also engaging said cap for locking the adjustment of said threaded member.
